UNITED STATES PATENT OFFICE.

STEPHEN GOLDINI, OF NEW YORK, N. Y.

THEATRICAL ILLUSION DEVICE.

1,178,444.

Specification of Letters Patent.

Patented Apr. 4, 1916.

Application filed June 26, 1915. Serial No. 36,437.

To all whom it may concern:

Be it known that I, STEPHEN GOLDINI, a citizen of the United States, residing in the city of New York, borough of Manhattan, county and State of New York, have invented a certain new and useful Theatrical Illusion Device, of which the following is a specification.

This invention is a theatrical illusion device, and the object of the invention is to provide a device by which a theatrical artist is enabled to carry on theatrical flashlight dancing through the use of either an alternating or a direct electric current.

Devices have heretofore been suggested to allow of flashlight dancing of the general character of the present invention, but the great disadvantage inherent in all of these devices is that they are adapted for use with direct current electricity only, they being of such character that it is impossible to give a performance which will be acceptable to an audience. As many theaters and playhouses are equipped with alternating current electricity only, the managers of acts employing such prior art devices are precluded from playing in such houses as are equipped with alternating current, their field of usefulness being limited only to such playhouses as are provided with direct current.

With the foregoing disadvantages in mind, the present invention embodies an appliance which allows of the performance of an act either with direct or alternating current, and the invention may be broadly stated as embodying a mat or mats on which the dancer treads, the tread surface of which mat or mats is provided with a plurality of upstanding wires on which the artist treads during the act of dancing. These upstanding wires of the one or more mats are electrically connected with a source of electrical current, either direct or alternating, so that, when an operator treads upon the surface of the mat with metallic-soled shoes, a circuit is completed, with the result that electric flashes are produced.

In one of its practical forms, the invention embodies a mat in the form of woven wire mesh, into which wire mesh is interwoven a myriad of small wires which extend upwardly from one surface of the mesh so that the appearance of said surface resembles that of a wire brush. This forms the

tread surface of the mat. Said mat is backed up with suitable insulating material so that, when laid upon a stage or platform, the current will not be dissipated.

Features of the invention, other than those specified, will be apparent from the herein-after detailed description taken in conjunction with the accompanying drawings.

In the accompanying drawings, I have illustrated different practical embodiments of the invention, but the constructions shown therein are to be understood as illustrative, only, and not as defining the limits of the invention.

Figure 1 is a diagrammatic view showing the manner in which two mats made according to the present invention may be coupled up in series, the circuit to be completed through metallic-soled shoes electrically connected. Fig. 2 is a detail section greatly enlarged, taken on line 2—2 of Fig. 1. Fig. 3 is a detail elevation of one of the current carrying units before assembling. Fig. 4 shows the same unit bent to secure the same to the body of the mat, and Fig. 5 illustrates a modified form of the invention wherein only one mat is necessary.

Referring to the drawings, and particularly Figs. 1 to 4, inclusive, A and A' designate a pair of coöperating mats. In this embodiment of the invention, each mat is provided with a base in the form of coarse woven wire mesh *a*, shown in detail in Fig. 2. The base is bound around its edges with suitable binding *a'* and its bottom is covered with any suitable insulating material *B*. At intervals throughout the mesh *a*, small lengths of wire *c*, shown in Fig. 3, are interwoven into the mesh *a*. In forming the structure shown in the drawings, units *c* of U-shape form are passed from one side of the mesh *a*, through the interspaced openings thereof, and are given a twist, after the manner shown in Figs. 2 and 4, to secure them to the mesh. Any number of these units may be employed, but it is preferable that a myriad of them are secured to the mesh so that the upper surface thereof resembles the bristling surface of a wire brush.

The mats thus formed are connected with an electric circuit *D* fed from a suitable source of electrical supply, either direct or alternating, and in circuit *D* is included a suitable resistance herein shown as a plu-

rality of lamps *d*. The mats *A* and *A'* thus constitute the electrodes of circuit *D*.

In carrying out a performance on the mats described, the artist is equipped with 5 a pair of metallic-soled shoes *e* which are electrically connected with one another through the medium of suitable wiring *e'* which extends from one shoe, up the corresponding leg of the operator, and down 10 the other leg to the other shoe. This wire is, of course, concealed from the audience by incasing the same within the stockings, or in any other suitable manner.

When an artist wearing the shoes described 15 dances with one foot on each mat, it will be manifest that, when both feet are connected with both mats, a circuit from electric circuit *D* will be completed through the shoes of the artist and the connecting wire *e'*. When the artist removes one or 20 both feet from the mats, the circuit will, of course, be broken, and the resistance *d* is sufficient to cause an arc to be made when either one or both feet leave the mat. The 25 current in circuit *D* is of considerable magnitude. As the artist carries on the act of dancing, and particularly as one of the metallic-soled shoes is in the act of leaving the mat, said shoe, having slightly depressed 30 the wires *c* upon its downward tread, will leave said wires in succession, *i.e.*, the shoe will not leave all of the wires at the same time, but, as the foot is raised, fewer and fewer wires will engage with the sole of the 35 shoe, in an indirect ratio to the distances which the foot takes in leaving the mat. As stated, the current in the circuit *D* is considerable, and it will thus be apparent that, as fewer wires contact with the shoe, 40 the amount of current which these wires must carry necessarily increases and becomes greater than said wires can carry, so that, when the shoe leaves said wires, a bright electric flash will ensue and small 45 particles at the very extremities of the wires will burst. This results as the foot leaves the mat, in a large number of electric flashes and flying sparks which resemble greatly the sparks which fly off an anvil when white 50 hot metal is struck a heavy blow, and, manifestly, this will be the case when either direct or alternating electric currents are employed.

Of course, the wires *c*, which form the 55 current carrying units as described, become, after continued use, flattened down to some extent, but this does not diminish the efficiency of the mats for the reason that the shoe, as it leaves the mat, will even then do so with diminishing point areas, which is entirely sufficient to produce such results as have never been heretofore attainable. Wires *c* are, however, preferably resilient 60 and return to upstanding position when the shoe is removed therefrom.

It may be here stated that it is not absolutely essential for the shoe to entirely leave the mat to produce the electrical effects referred to, as it is found in practice that the mere scraping of the shoe over the surface 70 of the mat is conducive to these effects. This is in marked contrast to devices heretofore employed wherein it was absolutely essential for the foot to leave the mat to produce any flash whatsoever.

The embodiment of the invention hereinbefore described is that which I generally prefer to employ, although I may, if desired, instead of providing two mats, use a single mat constructed in the manner shown 80 in Fig. 5. In this form of the invention, a base of insulating material *F* is provided, and upon this base is positioned two interlocking spiral bands *f f'* formed after the manner in which mats *A A'* are made. The 85 convolutions of these bands are the opposite electrodes of an electric circuit *D'*. Said bands do not come in contact with one another at any point and are thus normally insulated with respect to one another to 90 maintain an open circuit. An artist, in performing on this mat, mounts said mat with both feet fitted with shoes having metallic soles but having no connection with one another. As the artist dances about on the 95 mat, the metallic soles of the shoes bridge the distances between the convolutions of the bands *f f'*, with the result that the circuit is closed therebetween, through the soles of the shoes. This mat may be made any 100 size desired, so that the artist is free to cover considerable space, as in dancing about a stage. It will be understood that the electric circuit *D'* is fed from a suitable source of electrical energy and embodies suitable 105 resistance, after the manner shown in circuit *D* of the preferred embodiment of the invention.

Throughout the foregoing description and in the accompanying drawings, I have disclosed the preferred manner of producing a mat provided with a bristling surface, but it will be understood that this disclosure is for the purpose of illustration only, and that I consider the invention as broadly 115 novel as commensurate with the appended claims.

Having thus fully described the invention, what I claim as new, and desire to secure by Letters Patent, is:

1. In an appliance for electrical dancing, an electrode provided with a bristling, electrically conductive tread surface, in combination with electrical connections therewith adapted to supply current of sufficient 125 strength to produce disruptive discharges of the current upon the making or breaking of the current at the electrode.

2. In an appliance for electrical dancing, an electrode provided with a metallic base 130

and a bristling metallic tread surface of sufficient size to permit of dancing thereon.

3. In an appliance for electrical dancing, an electrode of sufficient size to permit of dancing thereon, embodying a metallic base provided with a multiplicity of small metallic protuberances on its tread surface.

4. In an appliance for electrical dancing, an electrode provided on its tread surface with small, upstanding, metallic projections, and electrical connections therewith adapted to supply current of sufficient strength to produce disruptive discharges of the current upon the making or breaking of the circuit at the electrode.

5. In an appliance for electrical dancing, an electrode provided with a metallic base, and small wires interwoven into said base, the free ends of which project above the tread surface of the base whereby a bristling surface is produced, in combination with electrical connections with said bristling surface, which connections are adapted to supply electrical current of sufficient strength to produce disruptive discharges of the current upon the making or breaking of the circuit at the electrode.

6. In an appliance for electrical dancing, an electrode provided with an uneven tread surface whereby an operator, when standing upon the tread surface of the electrode, engages the same in a series of point contacts, in combination with electrical connections with said point contacts, which connections are adapted to supply current of sufficient strength to produce disruptive dis-

charges of the current upon the making or breaking of the circuit at said contacts.

7. In an appliance for electrical dancing, the combination of a pair of electrodes of opposite polarity, each of which electrodes is provided with an uneven tread surface, an electric circuit in communication with said electrodes, and metallic-soled shoes co-operating with said electrodes whereby a circuit is completed from one electrode to the other through the metallic soles of the shoes, said electrical circuit being adapted to supply current of sufficient strength to produce disruptive discharges of the current upon the engagement or disengagement of the shoes with the electrodes.

8. In an appliance for electrical dancing, the combination of a pair of electrodes of opposite polarity, each of which electrodes is provided with an uneven tread surface, an electric circuit in communication with said electrodes, said circuit being adapted to supply current of sufficient strength to produce disruptive discharges of the current upon the making or breaking of the circuit at the electrodes, metallic-soled shoes, and means for electrically connecting said shoes whereby a circuit is completed through the shoes when an operator stands upon the tread surface of the electrodes, and broken when one or both shoes leave the surface of their corresponding electrodes.

In testimony whereof I have signed my name to this specification.

STEPHEN GOLDINI.
